FUEL INJECTOR PUMP

John R. Emerson, Flint, Mich., assignor to Borg-Warner Corporation, Chicago, Ill., a corporation of Illinois

Application February 11, 1949, Serial No. 75,757

11 Claims. (Cl. 103—38)

1

This invention relates to a fuel injector pump, and more particularly to a fuel injector pump of the single plunger variable stroke type, the length of the plunger injection stroke being controlled in accordance with engine manifold pressure, and distribution from the single plunger chamber to the various engine cylinders being controlled by a distributing disc.

Theoretically, the variable stroke injector plunger should provide the optimum control of fuel metering since in this type of pump when more fuel is required, the stroke is increased, whereas when less fuel is required, the stroke is merely reduced. Actually, it has been found very difficult in practice to construct a variable stroke injector type pump which would provide both efficient and satisfactory operation and at the same time the required flexibility of operation. Particular difficulty has been encountered in providing a variable stroke mechanical drive for the injection plunger. Further, while it is known to use manifold pressure or density as an indicator for metering, the control mechanism heretofore used has been bulky and excessively complicated.

An object of the present invention is to provide a new and improved fuel injector pump.

A further object of the present invention is to provide a fuel injector pump of the variable stroke type incorporating a simple and efficient mechanism for varying the length of the plunger stroke.

A further object of this invention is to provide in a fuel injector pump an improved pressure responsive control mechanism for operating the plunger stroke varying means.

In accordance with one embodiment of this invention, hydraulically operated means are employed to drive the plunger and to control the length of the plunger stroke. The pressure responsive control mechanism aided by a servo system changes the position of a stop plunger and the maximum stroke of the injector plunger as well as the volumetric capacity of the injector displacement chamber is determined by the position of this stop plunger. A supply pump of the straight spur gear type is incorporated in the injector pump, and not only supplies fuel for the displacement chamber of the plunger portion of the pump, but also supplies fuel under pressure to operate the fuel injector plunger and the servo piston in the variable stroke regulating control.

Other objects and advantages of the present invention will be apparent from the following

2

detailed description taken in conjunction with the drawings wherein:

Fig. 1 is a schematic diagram showing primarily the fluid pressure connections of the various parts of the injector pump of this invention;

Fig. 2 is a vertical, sectional view of the pump taken along the line 2—2 of Fig. 3;

Fig. 3 is a vertical sectional view taken along the line 3—3 of Fig. 2;

Fig. 4 is a detailed sectional view taken along the line 4—4 of Fig. 3;

Fig. 5 is a detailed sectional view taken along the line 5—5 of Fig. 2;

Fig. 6 is a sectional view taken along the line 6—6 of Fig. 2;

Fig. 7 is a sectional view taken along the line 7—7 of Fig. 2;

Fig. 8 is a sectional view taken along the line 8—8 of Fig. 2; and

Fig. 9 is a transverse sectional view taken along the line 9—9 of Fig. 8.

The fuel injector pump herein described and shown in the drawings is designed for use with a six cylinder engine in which the drive from the engine is one and one-half times engine speed and the distributing disc runs at one-half engine speed, or cam shaft speed, on a four cycle engine. However, the fuel injector pump of this invention could be used for example on a four cylinder engine if the drive from the engine were at engine speed and the gearing between the driven gear and the driving gear in the fuel supply pump were such that the distributing disc ran one-half engine speed. This is primarily a matter of gearing and requires but minor modification, the nature of which will be obvious to one skilled in the art from the following detailed description of this invention. Thus, while this invention is shown in the form employed for a six cylinder engine, it will be understood that by simple modification the arrangement of this invention can be adapted to an engine having either more or less than six cylinders.

The fuel injector pump of this invention comprises the following principal elements: a gear pump 10 driven by the engine for pumping fuel from the supply tank to the injector pump and for supplying the hydraulic pressure required in accordance with this invention. A variable stroke, hydraulically actuated injector plunger 37 supplies fuel under high pressure to a distributing mechanism, indicated at 59, which is connected to supply fuel under pressure to the cylinders of the engine (not shown) in rotation. The stroke of the injector plunger 37 is controlled

by a stop plunger 75, the position of which is regulated in accordance with manifold pressure by a pressure sensitive device 102 and associated servo means 103. Compensation for variation in atmospheric pressure is provided by a capsule 138 associated with the manifold pressure responsive device 102.

In Fig. 1, these elements are illustrated in simplified manner so as to make clear their related functions. Reference should be made to Fig. 1 as the following description is read to facilitate an understanding of the interrelation of the several components of the fuel injector pump of this invention.

Referring now to Fig. 2, it will be seen that the gear pump 10 is enclosed within the right portion of a fuel injector pump housing 11 and includes a large driven gear 12, supported on shaft 13 which is journaled in and rotatably supported by an elongated sleeve bearing 15 mounted in the left portion of the housing 11, as shown in Fig. 9. The driven gear 12 is of the straight, spur gear type generally employed in gear pumps and meshes at its lower side, as viewed in Figs. 2 and 6, with a similarly formed, driving gear 16 of substantially smaller diameter. Driving gear 16 is supported on and keyed to driving shaft 17, the shaft 17 extending to the right, as viewed in Fig. 2, and terminating outside the housing 11 in a spline 18 which is adapted to engage a suitable driving spline in the engine. Shaft 17 is journaled in a bushing 20, located on the right side of the gear 16, as viewed in Fig. 2, and packing 21 is provided adjacent the right end of the bushing 20 to prevent leakage of fuel from the pump into the engine, the packing 21 being retained by packing ring 22 and a helically coiled compression spring 23. When the pump is assembled on the engine, it is supported in position thereon by suitable bolts (not shown) carried by mounting flange 24 of the housing 11, the right end of the spring 23 then bearing against the engine housing.

The embodiment herein described of this invention is, as aforesaid, intended for use with a six cylinder, four cycle engine and the spline 18 on the shaft 17 is therefore arranged to engage a companion spline on the engine which rotates at one and one-half times engine speed. Driving gear 16 is selected with reference to driven gear 12 so that the shaft 13, which also drives the fuel distributing mechanism as will be more fully explained hereinafter, rotates at one-half engine speed, that is to say, the driving gear has a diameter one-third the diameter of the driven gear 12.

The gear pump 10 is provided with an inlet port 25 through which fuel is drawn from a supply tank (not shown) into the pump and the pump discharges through outlet port 26. The capacity of the pump is designed to be substantially greater than actually required for operation of the fuel injector pump so that a constant pressure may be maintained at the discharge port 26 in spite of wide variation in engine speed by a pressure regulating by-pass valve, indicated at 27 in Fig. 2. The by-pass regulating valve 27 is located above and to the right of the gear pump 10, as viewed in Fig. 2, being enclosed in a suitably formed portion of the housing 11, and is connected to the discharge side of the pump 10 so that pump pressure is applied to a plunger 28 of the by-pass regulating valve 27, the pressure tending to move the plunger 28 against a regulating spring 29. Discharge port 31 of the

regulating valve is connected to the inlet chamber 32 of the gear pump 10 so that by-passed fuel is recirculated through the system in conventional manner. The plunger 28 has a number of axially extending grooves 33 formed in its periphery and as the pressure against the plunger 28 from the pump 10 exceeds the counterpressure from the regulating spring 29, the plunger 28 moves to the left, as viewed in Fig. 5, thereby increasing the by-pass flow and tending to maintain a constant pressure for the output of pump 10. The by-pass operation of valve 27 is easily seen from Fig. 1.

Fluid pressure from the pump 10, regulated by the by-pass valve 27, is supplied from the outlet port 26 through a downwardly extending duct or channel 34, which connects at its lower end, as shown in Fig. 2, to an upwardly extending channel 35 and from the channel 35 to the underside of a piston 36. Piston 36 carries on its upper side a vertically disposed injector plunger 37, the lower end of which is rigidly secured to the piston 36. In order to provide for intermittent actuation of the plunger 37 in timed relation to the operation of the engine with which the pump is to be associated, a valving sleeve 38 is provided, the right portion thereof, as viewed in Fig. 2, being solid and secured to the left side of driving gear 16. The valving sleeve may be integrally formed with the shaft 17 to which the gear 16 is keyed and in any event is designed to rotate with the gear 16 and thus with the engine with which the pump is associated. Valving sleeve 38 is journaled in a long bushing 39 which is mounted in the housing 11 and the solid portion of the sleeve 38 has a transverse aperture or passage 40 formed therein, the ends of which register twice in each complete rotation of the sleeve 38 with the upper end of channel 35. Bushing 39 is suitably apertured at 39a and when aperture 40 is in register with the channel 35, it will be evident from Figs. 2 and 3, that a continuous passage is provided whereby fluid pressure from the pump 10 may be directed through a bushing 41 to the underside of piston 36. It will be noted that the upper end of bushing 41 is provided with oppositely disposed, transverse apertures 42 as well as the central aperture 41a, opening at its upper end against the underside 43 of the piston 36, whereby fluid pressure may be exerted uniformly over the underside of the piston. The cross-apertured upper end of bushing 41 is enlarged to form a shoulder 44 which seats on the lower edge of piston chamber 46, while the lower end of the bushing 41 is slightly spaced from bushing 39.

In one embodiment of this invention, the plunger 37 was made to have an area one-tenth that of the piston 36 and the pressure delivered by the plunger 37 was therefore ten times that applied to piston 36. Thus, where the regulated pressure of the fuel supply pump 10 is set at fifty pounds per square inch, the injection pressure to the engine cylinders will be five hundred pounds per square inch. Because of the high pressures present at the plunger 37, it is desirable to fit the plunger 37 very closely into cylindrical supporting block 43, which as may be seen in Figs. 2 and 3 is threaded into the midportion of the chamber 46 and has its lower end located substantially above the upper end of bushing 41. However, the piston 36 may be fitted somewhat more loosely in the lower portion of chamber 46 of the housing 11, since the piston 36 has no

metering function and there is an ample supply of pressure from the pump 10.

Since the driving piston 36 operates in a closed system, a fluid return path from the upper side of the piston to the inlet side of the fuel supply pump 10 must be provided as well as a return from the under side of the piston in order that the piston may move unimpeded. Fuel from above the piston 36 is returned to the inlet side of the fuel pump 10 through a return channel 45, shown in Fig. 3, one end of which communicates with the upper portion of the chamber 46 immediately beneath the plunger block 43 and the other end of which is connected to a further return channel 47, which leads to a channel 48 extending parallel to valving sleeve 38. A pair of oppositely disposed apertures 49 are formed in the hollow, left portion of the valving sleeve 38, being spaced somewhat to the left of the cross aperture 40 formed in the solid portion of the sleeve, as viewed in Fig. 2, and angularly displaced 90° therefrom. The apertures 49 are arranged to register through an aperture 49a in the bushing 39, with a short channel 48a connecting at right angles to channel 48, as shown in Fig. 8. Apertures 49 communicate through the hollow interior of the left portion of the valving sleeve 38 with a slot 50 formed in an extended, lower portion 51 of a dish-shaped cover plate 52. The cover plate 52 forms a part of the housing for the fuel distributor mechanism 59 and is suitably bolted to the pump housing at the left side thereof, as viewed in Fig. 2. The slot 50 extends upwardly and to the right, as viewed in Fig. 8, connecting at its upper end to a channel 53 which extends to the right, as viewed in Fig. 4, to the inlet chamber 32 of the gear pump 10.

Fuel is returned from under the piston 36 to the inlet chamber 32 during downward movement of the piston 36 through a drain channel 54, the right end of which, as viewed in Fig. 2, is connected to port 54a formed in the left side of the bushing 41 adjacent its lower end. Channel 54 has connected thereto a downwardly extending channel 55, the lower end of which is arranged to register through an aperture 55a in the valving sleeve bushing 39 with the cross apertures 49 formed in the valving sleeve 38 twice during a single revolution of the shaft 38. The discharge end of channel 55 is displaced 90° with reference to the discharge end of transverse channel 48a associated with return channels 45 and 47 and thus registration with apertures 49 occurs only when the apertures 49 are vertically aligned and the pressure path to the underside of piston 36 is closed. In Fig. 2 the apertures 49 are horizontally aligned, that is one of the apertures is registered with channel 48a permitting discharge from the upper side of the piston 36.

In accordance with this invention, the injector plunger 37 is positively actuated in both directions, fuel under pressure being supplied to the under side of the piston 36 when it is desired to inject fuel, and fuel under pressure being supplied to the upper side of piston 36 when it is desired to return the piston. Referring to Fig. 3, the pressure path to the upper side of driving piston 36 will be seen to include a transversely extending channel 56, the right end of which connects to the output port 26 of the gear pump 10 and the left end of which is arranged to register through an aperture 56a formed in bushing 39 with the cross aperture 40 in the valving sleeve 38 when this latter aperture is in horizontal alignment, as viewed in Fig. 3. When so aligned,

the end of the aperture 40 on the opposite side from the channel 56 registers with one end of a channel 51, bushing 39 being suitably apertured at 51a. The other end of channel 51 is connected to channel 47, and then through channel 45 to the upper side of the piston 36. When aperture 40 is aligned with channels 56 and 57, pressure is supplied through the channels 47 and 45 to the upper side of piston 36 forcing the piston downward. At this same instant, one of the apertures 49 in the valving sleeve 38 is aligned with channel 55 in the return path from the lower side of the piston 36, thus permitting fuel to be readily expelled from under the piston 36 as the piston moves downwardly. Thereafter, when the valving shaft 38 has been rotated 90°, pressure is applied to the underside of the piston 36 to force the piston upward through a pressure path including the bushing 41, aperture 40, channel 35, and channel 34 connected to pump discharge port 26. With this 90° rotation, one of cross apertures 49 is now aligned with the return channel 48a and fluid is permitted to drain from the upper side of the piston 36 as this piston is moved upwardly. Thus it will be seen that no impediment is presented to the movement of the piston 36 in either direction in which it is being driven.

Since the apertures 40 and 49 in the valving sleeve 38 will each register twice per revolution with their associated channels, the number of cycles of the piston 36 will be twice the number of revolutions of the driving shaft 17, and since this shaft is revolving at one and one-half times engine speed, the injection plunger 37 will make three complete cycles per engine revolution, thus giving three injection strokes per engine revolution, as required in a six cylinder engine.

Fuel from the fuel supply pump 10 reaches displacement chamber 58 above the injector plunger 37 through an upwardly extending channel 60, shown in Fig. 3, which is connected to the outlet port 26 of the gear pump 10 at its lower end, and has its upper end connected to a horizontally extending channel 61, best illustrated in Figs. 8 and 9. The lower end of channel 61, as viewed in Fig. 9, is arranged to register successively with arcuate slots 62 formed in a dish-shaped distributing disc 63, which rotates with the driven gear shaft 13. The disc 63 is enclosed by the cover plate 52 and is axially spaced therefrom to provide a chamber 64 lying on the opposite side of the disc 63 from that to which the channel 61 extends. The chamber 64 extends around the periphery of the disc 63, as clearly shown in Fig. 9, and the annular chamber 65 defined by the periphery of the disc 64 and the inner surface of the plate 52 communicates through a channel 66 with the displacement chamber 58.

The distributing disc 63 is rotated with the driven gear 12 by the shaft 13 which extends from the lower side of the gear 12, as seen in Fig. 9, a spline 68 being provided at the lower end of the shaft 13 and keyed to the dished portion of the disc 63. The distributing disc 63 fits closely against the end face of the housing 11 and is held firmly against this face by a thrust ball 70 and associated compression spring 71. The fuel pressure in the chamber 64 acting against the large surface on the lower side of the disc 63 in conjunction with the pressure of spring 71, maintains a sufficient pressure of engagement of the disc 63 and the housing 11 to provide the required seal.

As the injection plunger 37 moves downwardly,

one of the slots 62 registers with fuel supply channel 61 and fuel passes into chamber 64 and through channel 66 into the displacement chamber 58, as described. Thus, there is a combined action of supplying of fuel under pressure and a suction action on the part of the downwardly moving plunger 37 providing rapid filling of the injection chamber. The slots 62 are arranged to be out of registry with channel 61 when injection plunger 37 is moved upwardly so that fuel under injection pressure cannot be forced back into the supply system.

As the injection plunger 37 is moved upwardly by actuation of the piston 36, fuel is forced from the displacement chamber 58 back through the channel 66 to the chamber 64 on the lower side of the distributor disc 63. The pressure of the fuel forced back through the channel 66 is, of course, as many times greater than the initial supply pressure as is the area of the piston 36 greater than the area of the injection plunger 37. An arcuately slotted port 72 is formed in the distributing disc 63, and as shown in Fig. 8, is spaced radially outwardly of the slots 62. This port 72 is arranged to register successively with the inner end of each of six outlet ports 73 formed in the housing 11 and suitably connected to the various cylinders of the engine. It will be understood that the location of the outlet ports 73 is such that when the distributor disc port 72 is registered with one of the ports 73, the supply channel 61 is not registered with any of the slots 62 and thus full injector pressure is delivered only to the selected one of the ports 73.

In actual practice it has been found desirable to select the engine injector nozzle valves (not shown) so that these valves will not open at the fifty pounds pressure normally present at port 72. Thus, the discharge port 72 can be in full registry with port 73 before the injector plunger 37 starts its upward stroke. By having ports 72 and 73 in full open registry, as shown in Fig. 8, at the time the high injection pressure occurs, wire drawing of the fuel and erosion of the ports is avoided. Furthermore, this arrangement makes unnecessary accurate timing of the start of registry of these ports in order to obtain accurate timing of the fuel injection into the engine cylinders. In other words, the timing is dependent only on the start of the upward motion of plunger 37, that is, of the injection stroke.

It will be apparent from the foregoing that in accordance with this invention, there is provided a simple but efficient fuel injector pump wherein the injector plunger is hydraulically reciprocated by pressure supplied from the same pump which is employed to draw fuel from the supply tank. The structure thus far described employs a minimum of moving parts and where no variation in the length of the injector plunger stroke is required, this structure has been found to be very satisfactory. The structure described, however, is particularly well suited, because of the hydraulic drive, to regulation of the length of the injector stroke in accordance with one or more selected operating conditions or characteristics of the engine with which it is to be associated.

In accordance with this invention, the length of the stroke of the injector plunger 37 is varied from a minimum for idling the engine to a maximum for full throttle or full load engine operation, the length of the stroke of injector plunger 37 determining the quantity of fuel injected into each cylinder of the engine. In this embodiment of the invention, the plunger stroke length is reg-

ulated in accordance with engine manifold pressure, as this engine characteristic has been found to be a useful and reliable variable. However, it will be understood that other characteristics may well be substituted therefor or integrated therewith.

Referring to Figs. 2 and 3, it will be seen that the lower end of an adjustable stop plunger 75 extends into the displacement chamber 58 at the upper side of the injector plunger 37. The amount which this stop plunger 75 extends into the displacement chamber 58 determines not only the length of the injection stroke of plunger 37 but also determines the volumetric capacity of the displacement chamber thus regulating the amount of fuel which is drawn into the chamber on the downward stroke of the plunger 37. The plunger 75 is slidably journaled in a heavy cylindrical bushing block 76 which is, in turn, threaded in an enlarged upper portion 77 of the cylindrical chamber 46 of the housing 11 in the lower portion of which the piston 36 is journaled. The lower end of the block 76 is slightly spaced from the upper end of injector plunger block 43, this space providing the displacement chamber 58. A shoulder or flange 78 is formed about the mid-portion of the periphery of the bushing block 76 and seats on a suitable recessed ledge 79 at the upper edge of the chamber portion 77. Packing 81 is provided in the bushing block 76 and is disposed about the stop plunger 75 to prevent leakage therebetween, and the packing 81 is retained in position under compression by a gland nut 82 peripherally threaded into the lower end of the bushing block 76.

The position of stop plunger 75 with respect to displacement chamber 58 and injector plunger 37 is controlled by a cam 83, which is supported on a transversely extending stub shaft 84, the ends of which are suitably journaled in the two opposed walls of a U-shaped cam positioning block 86. The block 86 is slidably mounted in a suitably formed upper portion 87 of the housing 11, as shown in Fig. 2. Two adjustments are provided for the positioning of the stop plunger by cam 83. One adjustment comprises raising or lowering the cam by moving the block 86; the other comprises pivoting the cam on the shaft 84 by means of forked lever arm 85.

The cam positioning block 86 is vertically adjustable in housing portion 87 of the pump housing 11 by an adjusting screw 88 by which the block is supported in housing portion 87. The adjusting screw 88 is threaded in a suitably threaded aperture 90 formed in the upper end, that is, in the cross portion of the positioning block 86 and is provided with a shoulder or flange 91, the upper surface of which bears against the underside of the housing 87, the shank of the screw 88 extending upwardly through an aperture 92 formed in the housing 87. A knurled head 93 is provided on the upper end of the screw 88 to facilitate turning the same and a coiled spring 94 is positioned between the head 93 and the upper side of the housing 87 to hold the flange 91 against the underside of the housing 87. As may be seen in Fig. 2, a guide screw 95 is threaded into the left side of the housing 87 and extends into a longitudinal groove 96 formed in the periphery of the cam positioning block 86. Guide screw 95 prevents rotation of the cam positioning block as the adjusting screw 88 is rotated. A second screw 97 cooperates with the screw 95 to hold in position a flat spring 98, the upper end of which bears against the knurled surface of the

screw head 93 and prevents accidental rotation thereof.

As the adjusting screw 88 is turned, the block 86 is moved upwardly or downwardly, changing the position of the cam 83, and thus regulating the position of injection plunger 37 to obtain the best position for idling the engine. In practice, the idling position is set approximately correct at the factory and the amount of adjustment permissible is therefore preferably limited by a limit pin 99 which is mounted in and which extends transversely from one side of the knurled head 93. The pin 99 engages one side or the other of ratchet spring 98 to prevent the idle adjustment from being thrown too far out of line by an unskilled operator.

While the idling position of the stop plunger 75 may be manually regulated by adjusting the position of the cam positioning block in the housing portion 87, the position of the stop plunger 75 is, in accordance with this invention, also automatically regulated independently of the adjusting block 86 by pivoting the cam 83 on the shaft 84, in response to variations in a selected engine characteristic or operating condition. Referring to Fig. 3, it will be seen that there is provided in the upper portion of the housing 11 a longitudinally reciprocable, hollow, piston shaft 100 which has an annular groove 101 formed about the midportion thereof to receive and engage the upwardly extending bifurcated lever arm 85 of the cam 83. When shaft 100 moves to the right, arm 85 is pivoted in a clockwise direction and cam 83 is pivoted downward. Conversely, when shaft 100 moves to the left, arm 85 is pivoted in a counterclockwise direction and cam 83 is pivoted upward. When cam 83 is pivoted downward, stop plunger 75, the upper end of which is engaged by cam 83, is moved down into the chamber 58 to reduce the length of the injector plunger stroke, whereas when the cam 83 is pivoted upward, the stop plunger 75 is permitted to rise with respect to the injector plunger. It will be understood that in the operation of this fuel injector pump, there is always a minimum pressure in the displacement chamber 58 of the order of 50 pounds per square inch, using the figures earlier supposed. It has been found in practice that this minimum pressure exerted against the underside of stop plunger 75 is adequate to cause the plunger to follow the cam 83 at all times.

Movement of the piston shaft 100 to the right or to the left, as viewed in Fig. 3, is controlled by a pressure responsive mechanism, indicated generally at 102, which may be connected to the manifold of the engine. This mechanism will be described in detail hereinafter. Because of the relatively high pressures involved in the operation of the fuel injector pump of this invention, it is not feasible to employ the manifold pressure responsive mechanism directly to control the shaft 100 and therefore a servo system 103 is associated with the pressure responsive mechanism to provide the necessary operating power.

The servo system 103 includes a servo piston 104 secured to the right end of shaft 100, pressure for moving the piston 104 being supplied from the fuel pressure supply pump 10 through the discharge outlet 26 to an upwardly extending channel 105, connected at its upper end to channel 106, which is in turn connected to channel 107. The upper end of channel 107 registers with an axially elongated annular chamber 108 formed in the periphery of the servo piston 104 and bounded

on its outer side by the inner wall of a cylindrical servo piston chamber 110 formed in the housing in which the piston 104 is slidably journaled. Annular chamber 108 is connected through a radially extending passage 109 formed in the body of the piston 104 to an axially extending groove 111 formed in the periphery of a stem 112 associated with the pressure responsive mechanism 102. The stem 112 is journaled in the hollow piston shaft 100 and is longitudinally movable with respect to the shaft 100. The left end of groove 111 communicates with an aperture 113 formed in the shaft 100 on the left side of the piston 104, the aperture 113 in turn connecting to piston chamber 114. Pressure in the chamber 114 tends to move the piston to the right.

Pressure is supplied to the right side of piston 104 through an aperture 115 formed in the shaft 100 on the opposite side thereof from aperture 113 and communicating at its outer end with pressure chamber 114. The inner end of aperture 115 connects to a second axially extending groove 116 formed in the periphery of the stem 112, on the opposite side from groove 111, the groove 116, however, extending to the right end of the stem 112. A radially extending passage 117 formed in the piston 104 communicates at its inner end with the groove 116 and at its outer end with a short axially extending passage 118, also formed in the piston 104, which connects to piston chamber 119 on the right side of piston 104. Chamber 119 is defined by the piston 104 on the left side and by an end plate 121 of the housing 11 on its right side. Guide pin 122 fixed in the piston 104 extends at its inner end into the slot 116, thus preventing any relative angular motion between the servo piston 104 and the stem 112 of the pressure responsive assembly 102.

Fuel from the chamber 119 returns to the inlet port 25 of the gear pump through channel 123, shown in Fig. 3, which connects with channel 124, which in turn extends to an annular chamber 125 formed in the periphery of stroke control plunger bushing block 76. From the annular chamber 125 the return path comprises a vertically extending channel 126, shown in Fig. 7, pressure regulating valve 127, comprising the plunger 128 and spring 129, and vertically disposed passages 130 and 131 extending to the inlet chamber of the gear pump.

A definite differential pressure between chamber 114 and chamber 119, on the left and right sides respectively of servo piston 104 is available by virtue of the fact that the pressure from the fuel supply pump is regulated by the by-pass pressure regulating valve 27 at, for example, the previously described 50 pounds per square inch, while a substantially less pressure, for example 5 pounds per square inch, is maintained by the pressure regulating valve 121 in the return path to the inlet port of the gear pump. Assuming the figures stated, a 45 pound pressure differential is available to move the piston 104 to the right and to urge the stop plunger 75 downward. It will be understood that these pressure figures given may be varied substantially.

Stem 112 of the pressure responsive assembly 102 is fitted very closely within the piston shaft 100, since the relative linear position of the stem 112 with respect to the shaft 100, and particularly of the grooves 111 and 116 with respect to the apertures 109 and 115 respectively, controls the operation of the servo mechanism. It will be evident from the drawing that when the stem

112 moves to the right with respect to the piston shaft 100, the left end of groove 116 moves away from aperture 115, thus tending to close the passage and reducing flow of fluid therethrough to the chamber 119 on the right side of the piston 104. At the same time, the right end of groove 111 registers more fully with aperture 109, thereby increasing the flow to the chamber 114. This combined action increases the pressure differential between the chambers 114 and 119 and causes the piston 104 to move to the right in the usual follow action of servo mechanism to a position of balance. On the other hand, when the stem 112 moves to the left with respect to the shaft 100, the groove 116 registers fully with the aperture 115 and permits full flow therethrough, whereas the groove 111 no longer registers with aperture 109 reducing the flow and thereby reducing the pressure differential. The piston 104 then moves to the left to 20 a position of balance. In actual practice the servo system responds at once to any movement of the stem 112 and the relative movement of the stem 112 with respect to the shaft 100 will ordinarily never exceed a few thousandths of an 25 inch.

The pressure responsive assembly 102 which controls the position of shaft 112 comprises an aneroid bellows 132 completely enclosed in a cylindrical housing 133 which forms a part of 30 the housing 11 of the injector pump. Ports 134 and 135 are formed in the housing 133 and are spaced so that manifold air may not only be applied to the bellows 132 but will be circulated around the bellows, thus maintaining a uniform 35 temperature throughout the interior of the housing 133.

The bellows 132 is filled with dry air and sealed under standard conditions. When the engine with which this injector is operated is under full 40 throttle, and operating at sea level, the manifold pressure will be a maximum and then the bellows 132 is compressed, thus moving the bellows stem 112 to the left the maximum distance. Since the servo mechanism responds practically 45 instantaneously to any motion of the stem 112 and there is substantially no relative motion therebetween, the piston 104 may be considered as moving to the left with the stem 112 and to the same extent. Movement of the piston 104 to the left causes the piston shaft 100 to move to the left, thereby pivoting the cam 83 upwardly and permitting stroke control plunger 75 to move to its uppermost position. With the stop plunger 50 75 in its uppermost position, injector plunger 31 is permitted its maximum stroke.

As the air throttle of the engine is closed, the manifold pressure drops and consequently the pressure surrounding bellows 132 also drops permitting the bellows to expand and the bellows stem 112 to move to the right. The above described substantially instantaneous follow action of the servo mechanism 103 causes the cam 83 to be pivoted about the stub shaft 84 in a clockwise direction, thereby lowering the stop plunger 75 and thus shortening the stroke of injection plunger 31. It will be evident that by correctly designing the cam surface of the cam 83, any desired proportionate response to change in manifold pressure in the length of 55 the injection plunger stroke may be readily obtained.

It is essential to the operation of the stroke control mechanism that there be no leakage from the high pressure chamber 114 into the aneroid

bellows chamber. Accordingly, packing 161 is provided in recess 162 formed in the left end wall of the chamber 114 to engage in sealing relation the periphery of shaft 100. Packing 161 is retained in recess 162 by a helically coiled spring 163, the left end of which bears against the packing and the right end of which bears against the left, inner side of the piston 104. To prevent leakage of high pressure from between the stem 112 and the shaft 100, a sealing ring 157 is disposed between the left end of shaft 100 and stem 112, the ring 157 being disposed in a recess 164 formed in the left end of shaft 100, and retained therein by washer 158 carried by shaft 100. With this construction, an effective seal is had with minimum drag between stem 112 and shaft 100. To further avoid any possibility of leakage, the pressure between stem 112 and shaft 100 is reduced by providing a pressure bleed hole 155 in the piston shaft 100 immediately to the right of groove 101, as viewed in Fig. 3. Hole 155 registers with a wide, annular groove 156 formed in the periphery of stem 112 and permits pressure to escape from between the stem 112 and shaft 100 into a chamber 160 defined by the interior of the U-shaped cam positioning block 86 and housing 87. Chamber 160 is vented through a peripheral groove 159 formed in the stop plunger supporting block 76 and extending to the annular chamber 125, which latter chamber connects through pressure regulating valve 127 to inlet chamber 32 of the gear pump. In this manner, the pressure in the chamber 160 is reduced to a level corresponding to that of the piston chamber 119. Packing 165 is provided about the periphery of the left portion of shaft 100 to prevent leakage from the low pressure chamber 160 into the aneroid bellows chamber and is retained in recess 166 by gland nut 167 suitably threaded into the left wall, as viewed in Fig. 3, of the housing 87.

Because of the considerable forces involved, it has been found desirable to reduce insofar as feasible the friction between the cam 83 and the upper end of the stop plunger 75. Thus, in accordance with a preferred embodiment of this invention the upper end of the stop plunger 75 is enlarged and deeply recessed to provide a support for a ball 136. The ball 136 is freely rotatable within the recess in the upper end of the plunger 75 and the cam 83 rides on the upper surface of the ball. This permits adjustment of the position of the stop plunger 75 with a minimum of friction.

Since the fuel injector pump is driven from the engine, as hereinbefore described, it is supplied with speed sense, and because of the injector plunger stroke regulation in accordance with variations in manifold pressure, the fuel injector pump of this invention also has manifold air density sense and meters the fuel to the engine in response to both speed and load. However, as the airplane or vehicle goes into higher altitudes than sea level, the air pressure surrounding the engine drops, thereby lowering the exhaust manifold back pressure. With a given manifold pressure, the engine will consume more air under altitude conditions than at sea level and therefore would require more fuel than would be indicated by the manifold bellows 132. A correction must thus be made for this and in order to provide this correction in accordance with this invention, the pressure sensitive capsule 138 is supplied.

Referring to Fig. 3, the pressure sensitive capsule 138 will be seen to comprise a short bellows positioned within the housing 133, at the left end thereof, and attached at its right side by a rivet 139 to the aneroid bellows 132. The left side of bellows 138 is fixed to an externally threaded sleeve 141, threaded in the left end wall of housing 133. Sleeve 141 vents the capsule bellows 138 to atmospheric pressure, which is permitted to enter bellows 138 through a suitably perforated and screened, small, domed housing 142 mounted on the left end wall of the housing 133 and enclosing the left end sleeve 141. Adjustment of the position of the bellows 138 is made by loosening lock nut 143 and rotating the threaded sleeve 141 to obtain the desired position.

At sea level the bellows 138 will be more extended with a given manifold pressure in the housing 133 than under higher altitude conditions. Consequently, the bellows 138 will urge the bellows 132 to the right, thereby tending to pivot the cam 83 downwardly and to reduce the stroke of injection plunger 37. Conversely, the relative contraction of the bellows 138 under altitude conditions permits the bellows stem 112 to move to the left, which movement lengthens the injection plunger stroke for any given manifold pressure above the stroke length which would obtain at sea level for the same manifold pressure.

In accordance with this invention, there is also provided an idle cut-off. This is an important safety feature permitting the engine to be stopped with dry cylinders rather than wet cylinders as would be the case if the engine were shut off by simply switching off the ignition. A hot engine stopped with wet cylinders will often accidentally start if the engine is inadvertently turned over. Referring to Fig. 2, it will be seen that the lower end of the channel 35 by which fluid pressure is normally supplied to the piston 36 and which connects to the channel 34 also connects to a short channel 144. This channel extends to an idle control valve indicated generally at 145 and positioned in the lower part of the housing 11, as shown in Figs. 2, 4 and 7. The valve 145 comprises a cylindrical chamber 146 in which is rotatably journaled a relatively short valve sleeve 147. The left end of the sleeve 147 is closed, as viewed in Fig. 7, and a shaft 148 extends therefrom to a crank member 149 keyed thereto whereby the valve sleeve 147 may be rotated in the chamber 146. A helically coiled spring 151 is positioned within the right portion of the chamber 146 and the left end of the spring 151 bears against a suitably shouldered portion of the valve sleeve 147, the right end of the spring 151 bearing against chamber cap 152 threaded into the end of the chamber 146. As may be seen in Fig. 7, the valve sleeve 147 does not occupy the full length of the cylindrical chamber 146 in which it is located so that the right portion of the chamber 146 is open. Consequently, there is a constant supply of pressure from the channel 35 through the connecting channel 144 to the interior of the idle control valve 145. Cross apertures 153 are formed adjacent the left end of the valve sleeve 147 and are arranged to register with vertically extending channel 131 when the sleeve is suitably rotated by the crank 149. The channel 131 is connected to the inlet chamber 32 of the gear pump. Thus, by rotating the valve 147 in the chamber 146, the pressure supplied to the channel 35 may be varied or completely eliminated. With the idle cut-off valve sleeve rotated 90° from the position shown in Figs. 1, 4 and 7, 75

fuel under pressure from the fuel supply pump 10 is led back to the inlet side of the fuel supply pump. With this by-pass or bleeding of fuel from channel 35, there is no pressure to operate the plunger 37 and consequently the fuel injector pump will not supply any fuel to the engine.

Where herein the various parts of the fuel injector pump of this invention have been referred to as being located in a right or a left position, or an upper or lower position, it will be understood that this is done solely for the purpose of facilitating description and that the references relate only to the relative position of the parts as shown in the accompanying drawings.

What is claimed is:

1. In a fuel injector pump in combination, a pump housing, a supply pump in said housing comprising a pair of intermeshing gears, a supporting shaft associated with each gear and journaled in said housing, coupling means on one of said shafts for connecting said shaft in driven relation with a power source, means defining a fuel injector displacement chamber, an axially reciprocable fuel injector plunger journaled in said chamber, a piston operatively connected with said plunger for reciprocating the plunger in both directions, valving means for controlling application of pressure to said piston, said valving means being operated by said driven shaft, a fuel distributor chamber and a rotatable valving disc having a plurality of ports formed therein, passage defining means leading from said distributor chamber and adapted to be sequentially placed in communication with said chamber at selected angular positions of said valving disc, said valving disc being driven by the other of said pumping gear shafts, one of said passage defining means being connected to said fuel injector plunger displacement chamber and other of said passage defining means being connected to one or more fuel utilization devices.

2. In a fuel injector pump, means defining a fuel injector displacement chamber, an axially reciprocable fuel injector plunger journaled in said chamber, means for reciprocating said plunger, means for supplying fuel to said chamber, adjustable stop means projecting into said chamber and means for adjusting the amount said stop means projects into said chamber, said stop means being effective to vary the volumetric capacity of said chamber as well as to control the effective length of stroke of said plunger.

3. In a fuel injector pump, means defining a fuel injector chamber, a fuel injector plunger journaled in said chamber, hydraulic means for reciprocating said plunger, a stop plunger having a portion thereof disposed in said chamber engageable by said injector plunger for limiting the length of the injector plunger stroke in accordance with the amount said stop plunger projects into said chamber, said stop plunger controlling the volumetric capacity of said chamber in accordance with the amount said stop plunger projects into said chamber whereby upon a reduction in injector plunger stroke the volumetric capacity of the chamber is also reduced.

4. In a fuel injector pump in combination, a pump housing, a supply pump in said housing comprising a pair of intermeshing gears, a supporting shaft associated with each gear and journaled in said housing, coupling means on one of said shafts for connecting said shaft in driven relation with a power source, means defining a fuel injector displacement chamber, an

axially reciprocable fuel injector plunger journaled in said chamber, a piston operatively connected with said plunger for reciprocating the plunger in both directions, valving means for controlling application of pressure to said piston, said valving means being operated by said driven shaft, a fuel distributor mechanism in said housing including a fuel distributor chamber and a rotatable valving disc having a plurality of ports formed therein, passage defining means leading from said distributor chamber and adapted to be sequentially placed in communication with said chamber at selected angular positions of said valving disc, said valving disc being driven by the other of said pumping gear shafts, one of said passage defining means being connected to said fuel injector plunger displacement chamber and other of said passage defining means being connected to one or more fuel utilization devices, and a stop plunger having a tip portion thereof projecting into said chamber and engageable with an end of said injector plunger to limit the length of the injector plunger stroke, the volumetric capacity of said fuel injector displacement chamber being varied directly as a function of the length of the injector plunger stroke by said stop plunger.

5. In a fuel injector pump, a fuel displacement chamber, a fuel injector plunger movable in said chamber, means for moving said plunger in said chamber, and means operable independently of said plunger and effective to vary the volumetric capacity of said chamber, said means being also engageable with the plunger at one end of the plunger movement to serve as a limit stop for said plunger to regulate the effective length of plunger stroke in accordance with the volumetric capacity of the chamber.

6. In a fuel injector pump, a fuel displacement chamber, a fuel injector plunger movable in said chamber, means for moving said plunger in said chamber, and means operable independently of said plunger operating means for varying the volumetric capacity of said chamber, said means being also engageable with the plunger at one end of the plunger movement to serve as a limit stop for said plunger to regulate the effective length of plunger stroke in accordance with the volumetric capacity of the chamber.

7. In a fuel injector pump, means defining a fuel injector displacement chamber, an axially reciprocable fuel injector plunger journaled in said chamber, means for reciprocating said plunger, means for supplying fuel to said chamber, an adjustable stop means projecting into said chamber, and means for adjusting the amounts said stop means projects into said chamber effective to bear the volumetric capacity of said chamber as well as to control the effective length of stroke of said plunger, said last means including a servo mechanism responsive to pressure from said fuel supplying means.

8. In a fuel injector pump, means defining a fuel injector chamber, a fuel injector plunger journaled in said chamber, means for reciprocating said plunger, a stop plunger having a portion thereof disposed in said chamber engageable by said injector plunger for limiting the length of plunger stroke in accordance with the amount said stop plunger projects into said chamber, said stop plunger controlling the volumetric capacity of said chamber in accordance with the amount said stop plunger projects into said chamber, whereby upon the reduction in injector plunger stroke, the volumetric capacity of the chamber is

also reduced, means for supplying fuel to said fuel injector chamber, means for varying the position of said stop plunger, said last-mentioned means being responsive to pressure supplied by said fuel supplying means.

5. In a fuel injector pump, means defining a fuel injector plunger chamber, an axially reciprocable fuel injector plunger journaled in said chamber, pressure responsive means for reciprocating said plunger, means for supplying fuel under pressure to said pressure responsive means to reciprocate said plunger, means operable independently of said plunger effective to vary the volumetric capacity of said chamber, and means including a servo mechanism operatively connected with said last-mentioned means for providing the force required to position said last-mentioned means, said pressure supplying means also supplying fuel to said chamber and supplying pressure to operate said servo mechanism.

10. In a fuel injector pump, means defining a fuel injector displacement chamber, an axially reciprocable fuel injector plunger journaled in said chamber, pressure responsive means for reciprocating said plunger, means for supplying fuel under pressure to said pressure responsive means to reciprocate said plunger, means operable independently of said plunger effective to vary the volumetric capacity of said chamber, said means being also engageable with the plunger at one end of the plunger movement to serve as a limit stop for said plunger to regulate the effective length of plunger stroke in accordance with volumetric capacity of the chamber, and means including a manifold and atmospheric pressure responsive servo mechanism operatively connected with said volumetric capacity varying means for providing the force required to position said volumetric capacity varying means, said pressure supplying means being also connected to said chamber and said servo mechanism for supplying fuel to said chamber and for supplying pressure to operate said servo mechanism.

15. In a fuel injector pump in combination, a pump housing, a supply pump in said housing comprising a pair of intermeshing gears, a supporting shaft operatively connected with each gear and journaled in said housing, coupling means on one of said shafts for connecting said shaft in driven relation with a power source, means defining a fuel injection displacement chamber, an axially reciprocable fuel injector plunger journaled in said chamber, a piston operatively connected with said plunger for reciprocating the plunger in both directions, valving means for controlling the application of pressure to said piston, said valving means being operated by said driven shaft, a fuel distributor pump and a rotatable valving disc having a plurality of ports formed therein, passage defining means leading from said distributor chamber and adapted to be sequentially placed in connection with said chamber at selected angular positions of said valving disc, said valving disc being driven by the other of said gear shafts, one of said passage defining means being connected to the fuel injector plunger displacement chamber, another of said passage defining means being connected to one or more fuel utilization devices, means for varying to volumetric capacity of said fuel injector displacement chamber, said means including an atmospheric and manifold pressure responsive means and a servo mechanism operatively connected with said last-mentioned means for providing the force necessary to position the means

for varying the volumetric capacity of said fuel injector displacement chamber, another of said passage defining means connecting said supply pump to said servo mechanism, said servo mechanism and means for reciprocating the fuel injector plunger being responsive to the pressure supplied by said supply pump.
